UNITED STATES PATENT OFFICE.

HARRY M. BROWN, OF NEW KENSINGTON, PENNSYLVANIA.

CAR COUPLING.

Application filed August 19, 1924. Serial No. 732,940.

To all whom it may concern:

Be it known that I, HARRY M. BROWN, residing at New Kensington, in the county of Westmoreland and State of Pennsylvania, a citizen of the United States, have invented or discovered certain new and useful Improvements in Car Couplings, of which improvements the following is a specification.

In Letters Patent of the United States No. 1,429,186, granted me September 12, 1922, and No. 1,469,355, granted me October 2, 1923, I have described car couplers useful particularly in the coupling of mine cars and cars used for hauling materials in steel mills. My present invention concerns car couplers which, while not limited to any particular field of service, are adapted to like uses. The characteristics of the coupler of my present invention are simplicity of structure, attended by certainty in operation and durability in continued service.

A car coupler embodying my present invention is illustrated in the accompanying drawings. Fig. I is a view of two cooperating couplers, shown, one in side elevation, the other in vertical and medial section; Fig. II shows the same assembly, one of the pair being illustrated in plan from above, the other in horizontal section, on the plane indicated at II-II, Fig. I; Fig. III is a view in vertical and transverse section, on the plane indicated at III-III, Fig. I.

The coupler includes a head, and a coupling hook. The head is of the familiar bull-nose type. It may be secured to the car in any known and preferred manner. I here show it to be secured most simply, by being bolted directly to the sill of the car.

The head is formed conveniently of two castings: the main casting 1, slotted above at 2, to allow free swing of the hook, open below at 3, to allow the escape of scale and of foreign matter which might otherwise accumulate within, and flanged to rearward at 4, by which flange the casting may be bolted to the car-sill. The upper slot 2 does not extend to the forward edge of the casting, but the bull-nosed opening is rimmed about with a continuous web 5 of metal. A second casting 6 forms a hood for the upper slot 2 in the main casting. It too is flanged

to rearward, at 7, and bolted to place, may be applied and removed without disturbing the main casting, if the latter be already bolted to place. This second casting is further provided with webs 8 which, extending laterally, overlie the upper surface of casting 1, and more effectually protect the slot 2 from ingress of foreign matter. Furthermore, these webs 8 re-enforce the rim 5 of the bull-nose opening and strengthen it.

The hook 9 is mounted within the head and has two essential movements within the head. Its primary movement is that of rotation in vertical plane to and from the coupling position which is best shown in Fig. I. Additionally, it has a limited range of bodily movement longitudinally in the direction of the line of traction. In this connection it will be observed in Fig. I that the hook 9 at its anterior end is notched, at 10, and that when in traction position, this notch 10 engages from within the upper rim 5 of the bull-nose orifice of the coupler head. This engagement of the notch with the rim 5 of the orifice in the head prevents the hook when under traction from jumping out of coupling position and releasing the coupling link L, with which it is here shown to be in engagement. Toward its posterior end the hook 9 is provided with opposite trunnions 11, and these trunnions rest by gravity upon surfaces formed in the body of the head, so disposed as to allow the hook to swing to and from coupling position. The engagement, however, of the trunnions 11 with the head is such as to allow some forward and rearward movement of the hook as a whole within the head. This latitude for rearward movement of the hook is sufficiently indicated in Fig. I.

The hook 9 may be applied through the slot in the upper wall of casting 1 and be brought to operative position, with the trunnions 11 adjacent the bearing surfaces provided for them. It follows that casting 1 may be secured to the car, and, casting 8 being not yet applied, the hook may be introduced and brought to place, and after that the casting 8 may be applied, and so the assembly may be completed.

The coupling hook 9 rests normally un-

der the influence of gravity in coupling position. Its anterior face 12 is inclined. In the operation of coupling, a link L, bearing against this face 12, tends both to shift the 5 hook rearwardly through its limited range of longitudinal movement, and to swing it upwardly and pivotally. By such rearward displacement and vertical swing, the entering link passes beneath the tip of the hook, 10 and the hook then, released from the impulsion of the link, falls under gravity into coupling engagement with the link. When thereafter traction strain comes upon the assembly, the parts take the positions shown 15 in Fig. I. It is observed that in this coupling position the hook is so shaped that its surface of engagement with the link extends beneath the mid-plane of the link, and it will be perceived that this engagement with 20 the link from beneath, and the engagement of the notch 10 with the rim of the opening in the coupler head, effectually hold the link while under traction from jolting out of coupling engagement with link L.

25 The means for effecting uncoupling include a manually rotatable shaft 13, and a connecting rod 14. The shaft 13 at its ends is bent to form crank arms 15, accessible at the sides of the car for the operation of 30 uncoupling. Medially, the shaft 13 is bent to form a crank loop 16. With the loop 16 the connecting rod 14 is linked. The hook 9 on its upper surface is provided with a forwardly directed hook 17, and this forwardly directed hook is bifurcated, as is particularly shown in Fig. II. The connecting rod 14 is provided with an enlarged head 18. In assembly the rod 14 rests by 35 gravity upon the upper surface of hook 9, it extends between the bifurcations of the hook 17, and the head 18 of the rod engages from in front the forwardly directed hook 17. This will be clearly perceived on comparing Figs. I and II. The arrangement 40 is best illustrated in Fig. I. The assembly here is complete and the parts are in traction position. When uncoupling is to be effected, traction strain being relieved and the link L resting free within the head, 45 shaft 13 is, by means of one or the other of the hand cranks 15, turned clockwise. The consequent turning of the crank loop 16 clockwise has the effect, first, of drawing the hook 9 rearward, that is to say, from left 50 to right. Thus, the notch 10 is withdrawn from engagement with the rim at the forward end of the coupler head, and the anterior end of the hook is brought wholly beneath the slot 2. Further turning of the 55 shaft 13 and of the crank loop 16 in clockwise direction causes the hook 9 to turn clockwise on its trunnions 11, raising the anterior end and so effecting uncoupling. When thereafter the brakeman releases the 60 shaft 13, the hook returns under gravity to 65

position ready for automatic coupling, and as it so returns, it carries with it the rod 14 and causes the parts to resume substantially the positions shown in Fig. I. The castings 1 and 8 are recessed, as clearly appears in 70 Fig. I, to allow the free operation of the uncoupling mechanism, in the manner described. The recess R in the casting 1 is of sufficient width to admit of the introduction of the posterior end of hook 9 with its trunnions 11. 75

The bearing for the rotating shaft 13 may conveniently be formed between the two castings 1 and 6. This arrangement will be apparent on comparing Figs. I and II. 80

I have spoken of the trunnions 11 as affording pivotal movement for hook 9. It will be apparent on consideration of Fig. I, that the bearings for these trunnions, formed in casting 1, are merely plane surfaces or 85 substantially such, and that the turning of the trunnions 11 is effected when the trunnions are bearing against surfaces with respect to which there is looseness of play. This is permissible, because when the hook 90 is being turned, it is under no strain whatever. When it is under traction, the trunnions 11 are free and do not bear upon the surfaces of casting 1 anterior to them. The strain of traction is borne between the 95 notched forward end 10 of the hook 9 and the adjacent portion 5 of the coupler head.

It will be observed that no spring is included in this assembly; that when in operation the hook is wholly responsive to the 100 force of traction; that the uncoupling mechanism is under no strain whatever, except when actually in service to effect uncoupling. The operation of uncoupling does not require the brakeman to enter the space between the 105 cars. It will be observed that the mechanism is very simple, is strong to endure wear, and that the whole is easily accessible for assembly and replacement.

I claim as my invention:

1. In a car-coupler of bull-nose type, the combination of a coupler-head, a hook arranged within the head and capable of being shifted in right-line movement through a limited range and in the direction of traction, and capable also of swinging in a vertical plane to and from coupling position, the hook being further provided on its upper surface with an anteriorly-faced abutment, a rotatable shaft arranged to rearward of the said abutment upon the hook and provided with a forwardly and rearwardly swinging crank-arm, and a connecting rod linked to such crank-arm, and at its anterior end resting by gravity upon said coupling hook and in advance of said abutment and provided with a posteriorly-faced abutment adapted on the rotation of said shaft to engage the abutment on the hook. 115

2. In a car-coupler a coupler-head of bull- 120

nose type formed of two castings, the one slotted above, and the other forming a removable closure for such slot, a coupling hook pivoted within the casting first mentioned and applicable through the slot in the casting first mentioned to its position therein before the second-mentioned casting has been applied, and a hook-swinging shaft rotatable in bearings formed by and between the two said castings, when the second-mentioned casting has been applied. ¹⁰

In testimony whereof I have hereunto set my hand.

HARRY M. BROWN.
